UNITED STATES PATENT OFFICE

MARTIN H. KILGORE, OF BEAUMONT, TEXAS

DEEP-WELL PUMP

Application filed July 23, 1928. Serial No. 294,612.

This invention relates to deep well pumps and has for its object the provision of a pump which will deliver a continuous flow at the mouth of the well and which may be easily operated, may be produced at a low cost and which will be so constructed that the assembling and disassembling of the parts may be readily accomplished. The invention is illustrated in the accompanying drawing and 10 will be hereinafter fully set forth.

In the drawing:

Figure 1 is a sectional elevation of a pump embodying the invention, and

Fig. 2 is a vertical section of the upper end 15 of the plunger.

In the drawing, the reference numeral 1 indicates the working barrel of the usual form, and 2 indicates the delivery tube connected with the upper end of the working 20 barrel by a coupling collar 3. The upper end of the working barrel is internally beveled, as indicated at 4, and a barrel head 5 is fitted in said upper end, said head having a beveled portion 8 to correspond to the bevel 25 4, and the plunger above the head is constructed with an annular shoulder 9 adapted to impinge upon the head when the plunger is lowered into the well and by its impact drive the head firmly into seating engagement with the barrel. It will also be noted 30 that the head projects upwardly from the end of the barrel and is spaced annularly from the delivery tube, as shown at 10, whereby a space is formed in which any sand which 35 may be brought up with the liquid may collect to be subsequently removed. The plunger is a tube working slidably through but having a very slight clearance or close running fit in the head 5. The head is machined below its beveled surface so that its external diameter is reduced, as shown at 12, the lower extremity of the head being externally threaded and a grip ring 13 being fitted upon the reduced portion of the head and held 40 thereon by a nut or collar 14 engaged with the threaded lower extremity of the head. The external diameter of the grip ring is slightly in excess of the internal diameter of the barrel, and kerfs or slits 15 are cut 45 longitudinally therein alternately from its

opposite ends, the kerfs extending at least two-thirds the length of the ring. When the ring is forced into the barrel, the kerfs permit it to contract only sufficiently to enter the barrel and it effects a firm binding grip 55 with the barrel so that it will remain in place against pressure from the normal working upstroke of the plunger.

Upon the lower end portion of the plunger are fitted a plurality of packing cups 16 of the usual form, a collar 17 being fitted on the plunger above the top cup, and just above the collar 17 a plurality of ports 18 are formed radially through the plunger to establish communication between the bore of the 60 plunger and the annular chamber 19 between the same and the barrel. The packing cups have a close running fit with the barrel and are held in place by and between the collar or ring 17 and a stop ring 20 threaded onto the plunger at the lower end of the series of cups. The lower end of the plunger carries a valve 21 which opens upwardly and may be of any approved form, the upper end of its cage communicating directly with the interior of the plunger. In the lower end of the barrel is a standing valve 22 which may be of any approved form and is illustrated in a more or less conventional manner, while at the upper end of the plunger is a cage 23 constructed to be coupled to the sucker rod whereby the plunger may be operated. 70 75 80

In the practice of the invention, the head 5, grip ring 13, and the several packing cups together with the valve 21 and the parts co-operating therewith are assembled upon the plunger and the plunger is then lowered into the barrel so that the grip ring 13 will bind within the upper end of the barrel and the head 5 will enter and rest upon the beveled extremity of the barrel. By permitting the plunger to drop with some force, the annular shoulder 9 will then impinge upon the head 5 and wedge the same into the barrel so that a leak-proof joint will be provided around the plunger, as will be understood. Upon the down stroke of the plunger, the valve 21 will open so that the liquid admitted to the working barrel may rise within the plunger, a portion of the liquid passing through the ports 90 95 100

18 into the chamber 19 while the remaining portion will flow directly up through the plunger and the delivery tube to the mouth of the well. On the up stroke of the plunger, any liquid which may be retained within the plunger will, of course, be lifted to the mouth of the well and all the liquid which previously flowed into the chamber 19 will be compressed between the uppermost packing cup 16 and the lower end of the barrel head and, consequently, will be forced through the ports 18 into the plunger and be lifted to the mouth of the well. On this up stroke of the plunger, the valve 21 will, of course, close by gravity and by the pressure of the liquid above it and liquid will again flow through the standing valve to fill the barrel below the plunger. If it be desired, for any reason, to withdraw the plunger, a lifting force is applied to the plunger and the collar 17 will be brought against the barrel head and the nut 14 and it is possible to exert an upward pressure sufficient to dislodge the head and withdraw the pump from the well.

25 Having thus described the invention, I claim:

A pump including a working barrel, an upwardly opening standing valve in the lower portion of the barrel, a packing head constructed to bind in the upper end of the barrel, a tubular plunger reciprocable through the packing head and spaced from the barrel whereby an annular chamber will be formed between the barrel and the plunger, the packing head closing the upper end of said chamber, an upwardly opening valve carried by the lower end of the plunger and controlling flow into the plunger, a stop ring and a collar secured on the plunger above the valve, and packing held on the plunger by and between the stop ring and collar and constituting the bottom of the annular chamber whereby said chamber will be shortened and elongated as the plunger reciprocates, there being ports through the plunger immediately above the collar whereby liquid may flow through the plunger into the annular chamber on the down-stroke of the plunger to be compressed, returned through said ports and discharged from the plunger on the up-stroke of the plunger, and a cage at the upper end of the plunger, said cage having an external shoulder adapted to impinge upon the packing head to drive the same home and the collar being adapted to impinge against the head for withdrawing the same.

In testimony whereof I affix my signature.
MARTIN H. KILGORE. [L.S.]
